SMOKING PIPE

Earl C. Bunnell, Stratford, Conn.

Application July 8, 1938, Serial No. 218,052

12 Claims. (Cl. 131—184)

This invention relates to new and useful improvements in tobacco pipes.

An object of the invention is to provide a tobacco pipe so constructed that it may easily be kept clean.

Another object is to provide a tobacco pipe including means whereby it may be readily cleaned.

Other objects and advantages will become apparent from a consideration of the following detailed description taken in connection with the accompanying drawing wherein satisfactory embodiments of the invention are shown. However, it is to be understood that the invention is not limited to the details disclosed but includes all such variations and modifications as fall within the spirit of the invention and the scope of the appended claims.

In the drawing:

Fig. 1 is a view partly in side elevation and partly in section showing my improved pipe;

Fig. 2 is a sectional view taken as along the line 2—2 of Fig. 1;

Fig. 3 is a sectional view showing the manner in which the bowl of the pipe is cleaned;

Fig. 4 is a similar view showing the manner in which the stem portion of the pipe is cleaned;

Fig. 5 is a view somewhat similar to Fig. 1 but showing a slight modification; and

Fig. 6 is a side elevational view of the stem and cleaning tool of the pipe shown in Fig. 5.

Referring in detail to the drawing and at first more particularly to the form of the invention shown in Figs. 1 through 4, my improved pipe as there disclosed includes a bowl 10 and a hollow stem portion 11 communicating with the interior of the bowl in any or usual manner. As disclosed the stem 11 communicates with the interior of the bowl at the lower end thereof and an opening 12 is provided through the front wall of the bowl in alignment with the passage 13 through the stem portion. Opening 12 may be said to communicate with the passage 13 through the lower portion of the bowl.

In the manufacture of the pipe the opening 12 and the passage 13 may be formed as part of the same drilling operation. The outer or free end of the stem portion 11 may have secured thereto in any desired manner any of the usual mouthpieces 14 disclosed in the drawing as provided with an extension 15 of reduced diameter entering the outer or free end of the stem 11.

Carried by the pipe is a reamer or cleaning tool generally designated 16 and preferably formed of light-weight metal as aluminum. Tool 16 com-

prises an enlarged portion of head 17 which, as will later more fully appear, comprises a finger or hand piece for manipulation of the tool and which may be knurled as shown to facilitate gripping.

Inwardly of the head 17 the tool includes a shank 18 circular in transverse section but which at a point somewhat inwardly of the head 17 has been milled or cut away on its opposite sides providing an inner bifurcated portion including relatively long legs 19 and 20 each, when viewed in transverse section, somewhat in the shape of a double wedge (see Fig. 2) having relatively sharp longitudinal edges 21. Further each of the legs 19 and 20 is cut on a bevel on its inner end providing relatively sharp end portions 22. Obviously owing to their length the legs 19 and 20 may yield relatively as toward one another. The normal relation of these legs to one another is such that the entire tool 16 except for its head 17 may be inserted into the pipe through the opening 12 in the front wall thereof. Fig. 1 shows the tool in the described inserted position and there it will be noted that the bifurcated portion of the tool extends into both the bowl 10 and the stem 11 of the pipe whereby the tool does not cut off communication between the pipe stem and bowl but provides for the passage of smoke from the bowl to the stem (and thus to the mouthpiece 14) through the space between the legs 19 and 20. On its forward face bowl 10 should be provided with a flat surface about the opening 12 and in the drawing the bowl is shown as including a projecting portion 23 having a flat forward surface against which the under side of the head 17 engages when the tool is in the position of Fig. 1. The shank portion 18 of the tool as well as the legs 19 and 20 thereof frictionally engage the walls of the opening 12 and the walls of the passage 13 respectively whereby while under normal conditions the tool is properly retained in the pipe it may be easily withdrawn therefrom for use in cleaning the pipe as will now be described.

When the tool has been withdrawn for use, it may be used as a pick to dig out any "heel" in the bowl 10 and also the sharp ends 22 of the legs 19 and 20 may be used to dig loose any hardened material as for example a portion of any "cake" formed in the bowl. Somewhat similar to the sharp longitudinal edges 21 of the legs may be used to scrape the walls of the bowl.

The tool itself is very easily cleansed since it is not necessary to wipe it with or draw it through a ball of paper. Either after any hardened mat-

ter has been cut from the bowl or when no such matter is to be cut from the bowl a piece of paper may be applied to the bifurcated portion of the tool to form a mop or swab for cleaning of the 5 bowl.

This last is suggested in Fig. 3 wherein an end portion of a piece of paper 24 has been inserted between the legs 19 and 20, after which the tool is turned on its longitudinal axis to wrap the 10 paper about such legs 19 and 20 to form the mop or swab referred to. As the paper on the tool is inserted into the bowl the operator continues to rotate the tool and this has a further tendency to wrap the paper about the tool and also causes 15 the paper to wipe the side and bottom walls of the bowl.

The bowl being cleaned the passage through the stem 11 may also be cleaned. For this operation less paper is used and it is applied to the tool in 20 the manner above described but since a limited amount of paper is employed the same is wrapped rather tightly about the bifurcated portion of the tool. As the legs 19 and 20 are yieldable wrapping of the paper 25 (Fig. 4) about them 25 springs the legs slightly towards one another to allow for the thickness of the paper so that the legs with the paper wrapped about them may be inserted into the passage 13 through the opening 12.

30 After the insertion the operator continues to turn the tool about its own axis, so as to keep the paper wrapped onto the tool and to have the paper wipe the inner surface of passage 11. Turning movement of the tool in the same direction is continued as the tool with the paper thereon is withdrawn from the pipe. Obviously if desired, mouthpiece 14 may be removed and the tool with the paper thereon inserted into the passage 13 from the rear or outer end thereof. When 40 the cleaning operation has been completed the tool is re-inserted into the pipe as in Fig. 1.

Referring now to Figs. 5 and 6 the pipe there shown includes the bowl 26 carrying stem portion 27 with the outer end of which communicates 45 the mouthpiece 28 detachably connected with the stem as through the metal connecting piece or member 29. Metal member 29 serves also to connect with the mouthpiece 28 a cleaning tool 30 practically identical in construction with the 50 tool 16 with the exception that the tool 30 is secured to mouthpiece 28 and does not include any large head or finger portion and does include a tubular portion 31 extending into and secured to the metal member 29. Tool 30 includes the relatively long legs 32 and 33 corresponding exactly 55 with the legs 19 and 20 previously described and including relatively sharp longitudinal edges 34 and relatively sharp ends 35.

When the tool is in the pipe as in Fig. 5, smoke 60 may pass from the bowl 26 into the stem 27 through the space between the legs 32 and 33 and then into the passage 36 of mouthpiece 28 through the opening 37 in the reduced tubular portion 31 of the tool. When the pipe of Fig. 5 65 is to be cleaned the tool is withdrawn therefrom and being secured to the mouthpiece, as best illustrated in Fig. 6, may be used as described in connection with Figs. 3 and 4, the mouthpiece 28 functioning as a finger or hand piece for the 70 tool 30.

Having thus set forth the nature of my invention, what I claim is:

1. In a tobacco pipe including a bowl and a hollow stem portion communicating with the bowl, said pipe having an opening in its front wall 75

in alignment with and communicating through the bowl with the opening through said stem, a metal cleaning tool extending through said opening and into the stem and including a bifurcated portion providing a smoke passage between the 5 bowl and stem portion and a pair of spaced simultaneously operable entrances from the bowl into said passage, said tool withdrawable from the pipe for manipulation in cleaning said bowl and stem, and a finger piece on one end of the tool 10 for manipulating the same and comprising a portion of enlarged diameter shaped to abut the front wall of the pipe bowl about said opening therein when the tool is not in use.

2. In a tobacco pipe including a bowl and a hollow stem portion communicating with the bowl, said pipe having an opening in its front wall in alignment with and communicating through the bowl with the opening through said stem, a metal cleaning tool extending through said opening and 20 into the stem and including a bifurcated portion and spaced simultaneously operable entrances from the bowl into said passage providing a smoke passage between the bowl and stem portion, said tool withdrawable from the pipe for manipulation 25 in cleaning said bowl and stem.

3. A tobacco pipe cleaner comprising a metal member including a bifurcated portion, and said bifurcated portion having the opposing surfaces of its legs cut back at both longitudinal edges 30 whereby to provide flaring grooves to facilitate cleaning of said surfaces.

4. A tobacco pipe including a bowl and a stem portion communicating with the bowl, a metal member carried by the pipe and extending into 35 the bowl and stem portion, said member comprising a bifurcated portion providing a smoke passage from the bowl into the stem portion, said bifurcated portion comprising yielding legs having transversely curved outer surfaces extending 40 from the length of the legs and frictionally engaging the walls of the pipe and securing the member therein, and said bifurcated portion having the opposing surfaces of its legs cut back at both longitudinal edges whereby to provide flaring 45 grooves to facilitate cleaning of said surfaces.

5. A tobacco pipe cleaner comprising a metal member including a bifurcated portion, and said bifurcated portion having the opposing surfaces of the free end portions of its legs flaring away 50 from one another.

6. In a tobacco pipe including a bowl and a stem portion communicating with the bowl, a metal member carried within the pipe and extending into the bowl and the stem portion thereof, said member comprising a bifurcated portion defining between its legs a smoke passage between the pipe bowl and stem portion, the external diameter of the bifurcated portion of said member being substantially constant for the length of the member, 60 said member having the legs of its bifurcated portion resilient and engaging the inner walls of said stem portion for substantially the entire length of said legs and frictionally securing the member within the pipe for easy removal therefrom, and the legs of said member adapted to be forced toward one another to reduce the diameter of the member portion comprising said legs whereby after a thin piece of paper or the like has been wrapped about such member portion comprising 65 the legs it may be reintroduced into the pipe stem portion as a swab.

7. In a tobacco pipe including a bowl and a stem portion communicating with the bowl, a member comprising a bifurcated portion carried 75

- within the pipe and a handle at the outer side of the pipe bowl, said bifurcated portion comprising relatively long legs bevelled inwardly from their outer side surfaces and free ends to provide 5 digging tools for the digging of cake from the bowl, and said member frictionally held within the pipe by contact of said resilient legs with the walls of the pipe whereby the member may be removed and manipulated by said handle to clean the pipe.
- 10 8. In a tobacco pipe including a bowl and a stem, an instrument carried within the pipe and including a handle portion and relatively long yielding legs, the free end portions of said legs having arcuate longitudinally extending surfaces 15 conforming in curvature to the curvature of the inner surface of the stem, said legs set and having said arcuate longitudinally extending surfaces frictionally engaging the inner surface of the stem and thus removably securing the instrument in 20 place in the pipe, said instrument adapted to have a piece of paper anchored thereto by insertion of a portion of such paper between said free end portions of the legs, said instrument and paper adapted to be then given relative twisting move- 25 ment to wrap the paper about the legs to form a swab or mop of the free end portions of the legs, and said instrument then insertable into the stem to clean the same.
9. A tobacco pipe including a bowl and a stem 30 portion communicating with the bowl, a metal member carried by the pipe and extending into the bowl and stem portion, said member providing a smoke passage from the bowl into the stem portion, and said member constructed to 35 provide a plurality of radially spaced entrances from the bowl into said smoke passage, and said entrances so related that a plurality of them are simultaneously operable.
10. In a tobacco pipe including a bowl and a stem portion communicating with the bowl, a 40 member comprising a bifurcated portion carried within the pipe and a handle at the outer side of the pipe, said bifurcated portion comprising relatively long yielding legs each having a longitudinal edge wedge shaped in transverse section, said legs between them defining a smoke passage between the pipe bowl and stem portion, and 5 said legs frictionally engaging the walls of said pipe for substantially the length of the legs and by such engagement securing the member within the pipe whereby the member may be removed and manipulated by said handle for cleaning the 10 pipe bowl and stem.
11. In a tobacco pipe including a bowl and a stem portion communicating with the bowl, a member comprising a bifurcated portion carried within the pipe and a handle at the outer side of 15 the pipe, said bifurcated portion comprising relatively long yielding legs each having a longitudinal edge wedge shaped in transverse section, said legs between them defining a smoke passage between the pipe bowl and stem portion, said legs 20 frictionally engaging the walls of said pipe for substantially the length of the legs and by such engagement securing the member within the pipe whereby the member may be removed and manipulated by said handle for cleaning the pipe bowl 25 and stem, and said relatively long legs having sharpened free ends.
12. In a tobacco pipe including a bowl and a hollow stem portion communicating with the bowl, a detachable mouth piece connected with said 30 stem portion at the outer end thereof, a tool carried by the mouth piece and of greater length than and extending through said stem portion into the lower portion of the bowl above the bottom wall thereof, and said tool including a 35 bifurcated free end portion to permit of the passage of smoke through said stem portion from the bowl to the mouth piece and providing a plurality of radially spaced entrances each adapted for communicating the interior of the bowl with said 40 passage.

EARL C. BUNNELL.
